Primary Examiner — Lauren D Mcvey

(57) **CLAIM**

The ornamental design for a combined bookmark with light, as shown and described.

DESCRIPTION

FIG. 1 is a bottom, front, left side perspective view of a combined bookmark with light showing my new design; FIG. 2 is a bottom, rear, right side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines shown in the drawings depict portions of the combined bookmark with light that form no part of the claimed design.

1 Claim, 8 Drawing Sheets
